LAPEL EMBLEM

George A. MacCann, Pawtucket, R. I., assignor to
The Wallace Co., Inc., Providence, R. I., a corporation of Rhode Island

Application January 3, 1949, Serial No. 28

Term of patent 3½ years

(Cl. D29—2)

To all whom it may concern:

Be it known that I, George A. MacCann, a citizen of the United States, residing at Pawtucket, in the county of Providence and State of Rhode Island, have invented a new, original, and ornamental Design for a Lapel Emblem, of which the following is a specification, reference being had to the accompanying drawing, forming part thereof.

Fig. 1 is a front view of a lapel emblem, showing my new design; and

Fig. 2 is an edge view of the same.

I claim:

The ornamental design for a lapel emblem, as shown.

GEORGE A. MACCANN.
